CAM FOR KNITTING MACHINES

Oscar Fregeolle, Central Falls, R. I., assignor to
 Hemphill Company, Central Falls, R. I., a corporation of Massachusetts

Application May 13, 1943, Serial No. 486,802

2 Claims. (Cl. 66—50)

This case deals with a safety cam construction for knitting machines such as circular, independent needle knitting machines. In selecting needles, jacks or other instrumentalities in machines of the type concerned, the selecting movement is frequently divided into two parts, one of which merely moves the instrumentalities from a position in which they would not contact a cam for imparting the secondary movement to a position in which they will contact that cam, and the second part of the movement, one in which the instrumentalities which have been primarily selected are moved throughout a considerable extent to perform their intended function.

In machines such as Banner type hosiery machines the instrumentalities to be selected frequently have a plurality of removable selective butts and a master butt. The selective butts are broken away according to pattern requirements and those selective butts which are left intact are engaged by one or more selecting instruments or plungers. These selecting instruments or plungers are moved to and from an active butt engaging position according to a predetermined pattern.

The second movement imparted to instrumentalities of this type is preferably by means of a so-called master cam engagable with the master butt. Each of the instrumentalities will have one of said master butts and the construction is such that as a preliminary selective movement is imparted, the master butt will be so positioned as to engage and be moved by the master cam. Otherwise, under normal operation, the master butt will pass the master cam without engagement.

Upon changing the position of the selecting means or plungers engageable with the selective butts, it is frequently unavoidable that one of these plungers will be removed at such a time as to leave a selected instrumentality in a position somewhere between its non-selected and a completely selected position as the latter would be determined after passing the primary selecting mechanism. Such a condition gives rise to interference between the master butt and the master cam. If the master cam is solidly mounted, the butt will be broken upon engagement with the point of the cam, however, to avoid that, the master cam is customarily retained in position by spring means and is to move out on improper engagement with any of the master butts. The spring for maintaining the master cam in position must be fairly strong to avoid unintended cam movement, but if it has too much tension, butts

may be broken rather than the cam moving out as intended.

To avoid the above mentioned difficulties, the applicant has devised a safety cam functioning between the primary and the secondary selecting stages, this safety cam being very easily moved upon engagement by one of the master butts and functioning to return those instruments the butts of which are left in a half-way position by the primary selecting movement to a position in which they will safely pass beneath the master cam. Thus this safety cam has the advantage of providing a very easy movement which cannot result in breaking butts, also assures that partially selected instruments will be returned to a non-selected position.

In the figures of drawing:

Fig. 1 is a diagrammatic view, certain parts being shown in section, illustrating a typical selecting means for needle jacks to which the safety cam has been applied;

Fig. 2 is a section taken through the needle cylinder and cam mechanism showing a jack butt passing below the safety cam;

Fig. 3 is a section similar to Fig. 2, but showing the manner in which a completely selected jack is elevated so that its master butt passes above the safety cam;

Fig. 4 is a detailed view of the cam and the path of master butts which are affected by the cam; and

Fig. 5 is similar to Figs. 2 and 3 showing master butts being drawn down by the safety cam.

The invention is illustrated by showing as a typical example a simple selecting means for needle jacks. It is to be understood that it applies to control of any type of knitting instrumentality so long as that instrumentality has a selective movement imparted thereto and at a certain point in that selective movement, a change is made whereby the selected instrumentality may be left in an intermediate position. The cam applies to each individual selecting means, and if there are more than a single selection of the instrumentalities for each complete cycle, then as many safety cams as are necessary are provided.

Now referring to Fig. 1, a jack 1 has a plurality of selecting butts 2 and a master butt 3. That jack also has a butt 4 by means of which it is moved downwardly at certain times. The butts 2 and 3 are of the so-called saw-tooth type, but that is not essential since the invention applies to control of instrumentalities and butts of any shape. The selecting butts 2 are removable in

any desired manner preferably by being broken away as is now the common practice. For each of the butts 2 there is provided a selecting plunger 5 and these plungers are maintained in proper alignment to be engaged by their respective selective butts in the event the plunger is in active position and one of the butts 2 is left on the jack at that position. When selected by one of these plungers, the path travelled by one of the butts 2 indicated at line 6 changes to a slightly higher elevation as shown by line 7. The master butt 3 follows a parallel pathway first at line 8 and then at line 9.

Master cam 10 is so positioned and constructed that the master butts 3 only may contact it and if those butts move in line 8, they pass beneath the cam, that is, do not have any selecting movement whatsoever. If a jack is primarily selected by one of the plungers 5 so that the master butt then moves along line 9, that master butt will be raised by cam 10 to the elevation at line 11. The cam 12 is the usual raise cam and that levels the master butts prior to approaching the selecting plungers.

If in withdrawing one of the plungers 5 at a time when one of the butts 2 has travelled only part way along that plunger, or for any other reason, a master butt 3 will approach the point of cam 10 at an elevation somewhere between lines 8 and 9 so that it would neither travel below nor would it ride up the cam as intended, the safety cam presently to be described functions to move that butt and the jack to a position so that the butt will pass beneath cam 10. The safety cam is constructed as illustrated and has a cam portion 13 projecting inwardly at the upper end of a body portion 14 pivoted to swing about the pin 15. The pin 15 passes through a plate 16 and into the raise cam 12. A sort of groove or slot is formed in the raise cam and the body portion 14 of the safety cam is so designed that as shown in Fig. 1, the groove acts as a stop preventing movement of the cam toward the plungers 5 and in the other direction as shown in Fig. 4, prevents movement oppositely or in the direction of cam 10. A spring 17 attaches at a fixed point and to the upper end of the safety cam maintaining it in the position of Fig. 1 except as contacted by one of the butts 3 at which time it swings to the position of Fig. 4.

The cam portion 13 is bevelled at about the same angle as the top of a butt 3 and is also bevelled at the forward edge and at its rear part so as to guide butts downwardly beneath the cam no matter what the direction of approach of passing jacks and their butts.

The pivot 15 is to the right of the cam part 13, Figs. 1 and 4, and that causes the cam 13 when engaged by one of the butts 3 to swing to the position of Fig. 4 and thereby to rise and to assume an inclined attitude. Normally cam 13 is in such a position that a butt 3 riding along the raise cam and whose jack is not affected by any one of the plungers 5 will pass beneath cam 13, Fig. 2. Selected jacks will be elevated to such an extent that their butts 3 will move above the cam 13, see line 9 and Fig. 3.

When contacted by a butt moving at an intermediate position, the cam will be swung to the right, Fig. 4, thereby elevating the front edge of the cam above the top of the butt whereupon that butt will then be lowered sufficiently so that it must pass beneath cam 10. Such action is illustrated in Fig. 5 and the path one of the butts 3 would thus follow is shown in Fig. 4. If several

butts pass at one time, the first will swing the cam 13 to the position of Fig. 4 and it will remain in that attitude until all of those butts have passed beneath it whereupon spring 17 will return it to its original position.

If, when the cam 13 starts to swing to the right, Figs. 1 and 4, there are butts 3 just above it, those butts will merely be pushed upwardly and will strike cam 10 at a still higher level.

10 A so-called double sole cam 18 functions upon the butts 4 and will lower jacks which have been primarily selected, but which are not to complete that selecting movement. This cam functions in advance of cam 13 so that all butts 3 on jacks having one of the butts 4 and while cam 18 is active, will pass beneath cam 13.

For reciprocatory work the cam 13 is so bevelled that butts passing in reverse strokes are guided beneath the cam and thus there is no improper functioning or interference at that time.

20 The invention has been described by reference to one specific embodiment of the same, but it is to be understood that many variations may be resorted to without departing from the scope of the invention as originally conceived.

25 The application to jacks of the type shown is merely illustrative and other instrumentalities are equally well controlled, also the selecting butts themselves may be of other shape, for example, 30 may be square or rectangular in shape rather than of saw-tooth construction. Circular machines are only one type of knitting machine to which the invention applies and it may equally well be used in straight machines or in any other type machines where instrumentalities are selected and the instrumentalities and cams have relative movement. The invention is limited only by the scope of the appended claims.

I claim:

40 1. In a knitting machine, the combination of instrumentalities having selecting butts and a master butt, selecting means for said first mentioned butts and a fixed master cam engageable with said master butts; a safety cam positioned between said selecting means and said master cam and having a cam surface sloping downwardly toward said master cam, said safety cam also being pivoted so that its cam surface can swing upwardly and toward said master cam in 45 order that any master butts positioned so as to collide with the end of said master cam will engage said safety cam and, if necessary, swing it until said butts are caused to move downwardly along said cam surface to a position in which 50 they can pass below said master cam.

55 2. In a knitting machine the combination of

instrumentalities having selecting butts and a master butt, a plurality of selecting plungers operable on selecting butts and a master cam engageable with the master butts, the construction being such that the withdrawal of a plunger may leave one or more of the master butts in such position as to contact improperly with the master cam, a safety cam between said plungers and master cam pivoted to swing in the direction of said master cam upon contact with any of said improperly positioned butts, said safety cam also having a downwardly sloping cam surface adapted to rise when its end is engaged by a butt until said butt moves from contact with said end onto said cam surface whereby it is guided to a position in which it will pass beneath said master cam.

OSCAR FREGEOLLE.
